UNITED STATES PATENT OFFICE

CHARLES E. ACKER, OF OSSINING, NEW YORK, ASSIGNOR TO THE NITROGEN COMPANY
A CORPORATION OF NEW YORK.

METHOD FOR PRODUCING NITROGEN COMPOUNDS.

1,160,811.

Specification of Letters Patent. Patented Nov. 16, 1915.

Application filed September 2, 1910. Serial No. 580,190.

To all whom it may concern:

Be it known that I, CHARLES E. ACKER, a citizen of the United States, residing at the city of Ossining, in the county of West-
5 chester and State of New York, have invented certain new and useful Improvements in Methods for Producing Nitrogen Com-
pounds, of which the following is a full, clear, and exact description.

10 This invention relates to a process for the manufacture of alkali metal cyanids, cyanamids and the like, and more particularly to certain improvements in the processes de-
scribed in my United States applications,
15 Serial No. 485,344, filed March 23, 1909, and Serial No. 579,763, filed August 30, 1910. The processes therein disclosed consist in initially reacting on a particularly "reactive metal" such as barium, lithium, strontium,
20 manganese, etc., with carbon or a carbonaceous reagent for the purpose of producing a carbid of such metal, *e. g.*, barium carbid; in then treating this carbid with nitrogen or a nitrogenous reagent, for the purpose of
25 producing the cyanid of such metal, and in finally reacting on the barium cyanid or the like with an alkali metal *e. g.*, sodium, with the consequent production of sodium cyanid and metallic barium. In the first applica-
30 tion, the reactions involved occur within the body or mass of a molten alloy, such alloy preferably comprising the alkali metal, the reactive metal and a relatively inactive diluent metal; while in the second case the
35 reactions resulting in the formation of car-
bid were confirmed principally to the sur-
face of the alloy, the subsequent reaction of the carbid so formed with a nitrogenous reagent occurring in the body of a mass of
40 superposed fused salt. As I stated in the second of the applications aforesaid, the formation of the final product was expedited and the process made more efficient by bring-
ing about the reaction between the carbon
45 and nitrogen compounds entirely outside of the body of alloy, and I have since found that a still greater increase in efficiency may be obtained by causing all of the reactions to occur in the body of fused salt. This applica-
50 tion therefore relates to a process of this description, and covers the feature of electro-
lytically depositing both the reactive metal

and the alkali metal on a suitable cathode from the molten alloy, using a suitable electrolyte, such for example, as sodium cyanid; 55 and in introducing nitrogenous and carbonaceous reagents into the electrolyte in such manner that the same may come directly into contact with the liberated metals. As stated in application 485,344, some portion of the 60 "reactive metal" *e. g.*, barium, might combine directly with nitrogen to form barium nitrid which would then react with carbon to form barium cyanid; and that this cyanid would in turn be decomposed by sodium as 65 above, with formation of sodium cyanid and metallic barium. I stated, furthermore, that both carbid and nitrid might be formed under the conditions of the processes, and that they might then react together to form 70 "reactive metal" cyanid, *e. g.*, barium cyanid, which would be similarly decomposed by metallic sodium. As stated in the second application, by far the greater part of the final product is produced as a result 75 of the initial formation of "reactive metal" carbid, *e. g.*, barium carbid, in what seems to be a particularly favorable physical condition for the absorption of nitrogen at a low temperature; and that a comparatively 80 small proportion of the final product is obtained as a result of the initial formation of "reactive metal" nitrid which afterward combines with carbon, etc.

The chemical reactions involved in the 85 present case, when sufficient free carbon is present, are substantially similar to those described in my applications above referred to, and may be represented as follows:

If anhydrous ammonia is employed in- 95 stead of free nitrogen, the second of the above equations will be as follows:

It will be observed by considering reac- 100 tions No. 1 to No. 4 representing the principal steps of the process) that the "reactive metal", *e. g.*, barium, passes from the metallic state to carbid, carbid to cyanid, and

from cyanid back to the metallic state, and that it thus becomes available for reuse.

As stated in my other applications the "reactive metal" *e. g.*, barium, and the alkali

- 5 metal, *e. g.*, sodium, may each be employed in the pure state, in the form of an alloy with each other, or in the form of an alloy with certain heavy and relatively inert metals such as lead, tin, etc.; the nitrogen 70
- 10 may be employed in the form of pure or diluted gas, ammonia, or other nitrogenous reagent; and the carbon may be employed in the form of finely divided, granular, or lump charcoal, coal, coke, hydrocarbon gas, 75
- 15 fuel oil, lamp black, a cyanid, cyanamid or other carbonaceous reagent. By the term "carbonaceous reagent" as used in the appended claims, I mean therefore, carbon or any compound thereof capable of yielding 80
- 20 carbon under the conditions of the process; while the term "nitrogenous reagent" correspondingly refers to and includes nitrogen or any compound including nitrogen as an ingredient thereof, which will yield that 85
- 25 element under such conditions.

If the source of carbon is a gas, fuel oil, or lamp black, the resultant carbid, produced by the combination of the "reactive metal" with carbon (as pointed out in application No. 485,344) is found to be present in finely divided form.

As stated in application 579,763 filed August 30, 1910, the carbid produced in the process, is in peculiarly favorable physical 35 condition for the absorption of nitrogen, being apparently amorphous and impalpable and quite unlike the ordinary hard, iridescent, impure commercial crystalline carbids known to commerce. The former is 40 produced at a very low temperature (generally below 900° C.) and under radically different conditions from the later, which is produced in electric smelting furnaces at a very high temperature,—generally over 45 1300° C.

When both barium and sodium are alloyed with a heavy metal such as lead, and so utilized in the process,—some of the reactions in which barium, sodium, carbon, etc., 50 are concerned must obviously take place in the actual presence of the alloy—either at the surface thereof or in contact with some part of the molten mass of metal; thus the carbonaceous reagent in order to combine 55 with the barium in the alloy, must be brought into actual contact with the alloy—and barium cyanid, in reacting with sodium (reaction #3) must come into actual contact with sodium as contained in the alloy. 60 In my latter application, also, I called attention to the fact that the presence of a considerable body of molten sodium cyanid on the surface of the alloy was an advantage, in that the barium carbid became suspended, diffused, or dissolved in the cyanid 65

and could there be more advantageously reacted upon by the nitrogenous reagent, the product of the reaction being barium cyanid, which fused readily and dissolved in the sodium cyanid and thus came into contact with the metallic sodium contained in the alloy, at the surface thereof, whereby the barium in the barium cyanid was set free at the surface of the alloy, and sodium cyanid was formed; and further that the metallic barium thus liberated at the surface of the alloy promptly combined with carbon to form more carbid, which then became disseminated throughout the molten cyanid as before. 80

When metallic barium is liberated at the surface of the alloy, it may reenter the alloy, if only momentarily, and then afterward combine with carbon in contact with the surface of the alloy at that particular point 85 to form barium carbid; at any rate the decomposition of the barium cyanid is effected by the sodium at the surface of the alloy, and not elsewhere in the mass of molten cyanid. It thus transpires that some of 90 the intermediate reactions of the process as carried out in the apparatus described in application Serial No. 579,763 take place at the surface of the alloy only and that they are effected by certain metals while 95 diluted with other metals, and which are therefore to some extent less effective in bringing about such reactions than they would be if in the pure state, and not diluted, so to speak, with other relatively inert 100 metals.

I have found it desirable in carrying out these reactions at the surface of the alloy to have a comparatively high percentage of both "reactive metal" and alkali metal present in the alloy, so that they will not be unduly diluted in which case the process proceeds smoothly and rapidly,—but I have also found that it is possible and convenient to liberate from the alloy—and within the mass 110 of the molten cyanid itself—both "reactive metal" and alkali metal in the pure state, that is to say, not in the least diluted with an inert metal such as lead, (although the two metals actually concerned in the reactions, *e. g.*, barium and sodium, when simultaneously liberated in the interior of the molten cyanid may be momentarily alloyed with each other) by passing a current of 115 electricity from the surface of the molten alloy constituting an anode, through the molten cyanid constituting an electrolyte, to a solid carbon, iron or other metal disk or grid, partly submerged in the cyanid, and constituting the cathode of an electrolytic 120 cell. The metallic barium thus liberated within the mass of the molten cyanid instantly combines with carbon—either the carbon of the cathode, if the cathode be of carbon, free carbon disseminated throughout 125

the molten cyanid, according to reaction No. 1, or combined carbon in the molten cyanid itself—the latter according to the following equation:

If employing a solid iron or metal cathode, as I prefer, and in case there is no free carbon disseminated or diffused throughout 10 the molten cyanid, the above reaction (#5) will always take place when barium is the reactive metal used.

The same reaction will take place when 15 lithium, or some other "reactive metal" is employed instead of barium. The products of the reduction of the sodium cyanid are thus, sodium cyanamid (dialkali cyanamid) and barium carbid, and if no free carbon is present or afterward supplied, the reduction 20 of the cyanid to cyanamid will proceed until the entire mass of cyanid is converted into cyanamid, and the process may be used accordingly for the production of alkali cyanamids. When, however, free carbon is 25 present in the molten mass at the time the barium is liberated in a free state, or whenever it is afterward supplied, the cyanamid which is probably always formed within the molten mass is quickly reconverted into cyanid. When metallic barium, or other "reactive metal" is set free at the surface of the 30 solid cathode, and within the mass of molten sodium cyanid it probably does not preserve its metallic character for more than a brief 35 moment, but combines with carbon practically at the moment of its liberation.

I regard it as likely, in view of the fact 40 that barium does reduce molten sodium cyanid to sodium cyanamid by combining with some of its combined carbon, and in view of the fact that molten sodium cyanid is in intimate and close contact with the barium at the moment of its liberation,—pressed against it in fact by the weight of the supernatant fluid cyanid, and in view of the impalpable and amorphous character of the barium carbid produced in the process at so 45 low a temperature (below 900° C.) that the greater part of the barium carbid, which is concerned in the synthesis of sodium cyanid by this process is produced by barium combining with one element of carbon in the cyanid itself,—it being understood, of course, that but a very small proportion of 50 the whole mass of cyanid would be thus momentarily reduced—and that the free carbon floating around therein quickly reconverts the reduced portion back to cyanid.

The barium carbid, produced in accordance 55 with reaction #1 or reaction #5, remains suspended in the molten cyanid by reason of the agitation of the molten mass.

The entire mass of cyanid is practically 60 saturated with impalpable carbid, and if a sample of the molten cyanid taken during

this process is moistened with water, the presence of carbid is very evident from the odor of the evolved acetylene,—although no lumps or crystals of carbid may be visible. The carbid is present in a very fine state of 70 division. (Some carbid may also possibly be in actual solution.) When the cyanid is examined under the microscope the pure colorless crystals of cyanid loom up very large and clear, and squeezed in between the 75 crystals is the dark gray or black carbid apparently in the form of a film. The moisture in the air attacks this film of carbid between the crystals at the exposed edges of the film and minute bubbles of gas are constantly given off all along the exposed edges. Evidently the carbid is in very soft condition since it is squeezed into the thin spaces between the crystals of the cyanid in the manner described; but it is impossible to 85 examine it directly in the open air on account of the minute bubbles of gas which instantly cover its surface.

The specific gravity of barium carbid is considerably greater than that of molten 90 sodium cyanid, but owing to the fact that the carbid is apparently in amorphous condition, a little agitation suffices to maintain it in suspension.

The gaseous nitrogen or ammonia, or a 95 little fuel oil, injected into the alloy, or into the molten cyanid, and used primarily as a source of carbon, produces all the agitation required to maintain both the carbon and amorphous carbid in suspension in the molten cyanid. Meanwhile, nitrogen or ammonia is continuously or intermittently introduced into the mass of molten cyanid in such manner as to come into contact with the suspended carbid with which it then combines to form barium cyanid, which fuses easily, and being perfectly miscible with the sodium cyanid, diffuses throughout the entire molten mass. Barium cyanid is thus constantly present throughout the molten electrolyte and at the very surface of the solid cathode where metallic sodium is liberated. It may be liberated simultaneously with the barium. As soon as pure sodium is liberated at the cathode it enters into reaction with the barium cyanid (reaction #3) to form more sodium cyanid and to again liberate pure barium in the mass of the cyanid itself; and not at the surface of the alloy. The pure metallic barium therefore does not reenter the alloy, for notwithstanding the fact that its specific gravity is considerably greater than that of the molten electrolyte it cannot settle through the electrolyte without coming in contact with carbon, either free or combined, and uniting therewith to form barium carbid. It thus transpires that as long as there is any barium cyanid in the melt—under normal working conditions it should always be present 110

115
120
125
130

until the charge is to be finished—the liberated sodium is utilized as fast as it is set free at the solid cathode and therefore does not accumulate as such within nor on the 5 surface of the melt. If the residual lead alloy should contain a sufficient percentage of sodium to react with barium cyanid in the electrolyte, then such alloyed sodium when reacting with barium cyanid at the 10 surface of the alloy, will liberate the barium at the surface of the alloy, and it may then combine in whole or in part with the heavy, inert metal of the alloy; but by far the greater part of the final product will be produced as a result of intermediate and final 15 reactions taking place within the mass of the molten cyanid at the surface of the solid cathode, or in the vicinity thereof.

The present process may be conducted in 20 a double compartment electrolytic furnace similar to the sodium furnace described in application Serial No. 575,189, filed August 5, 1910, except that the solid cathode has a hole in its shank for introducing nitrogen 25 (and fuel oil, if desired), and that the iron cover is preferably fitted with a hopper.

Referring therefore to the accompanying drawings, which illustrate one form of apparatus which may be used: Figure 1 is a 30 vertical cross section of an apparatus adapted for the carrying out of my improved process taken on the line I—I. Fig. 2 is a horizontal section through the said apparatus taken on the line II—II of Fig. 1. Fig. 3 is a transverse vertical section of said 35 apparatus taken on the line III—III of Fig. 2. Fig. 4 is a fragmentary section taken on line IV—IV of Fig. 3.

Like parts are designated by the same 40 reference sign throughout the respective views.

Referring now to the drawings, the furnace or inner container 1 should preferably be made of cast iron or cast steel, and the 45 inner walls of such chamber should preferably be lined with refractory material 2, such as alumina or magnesia. The furnace casting is inclosed at the bottom and on all sides by heat insulating material 3, preferably brick or the like. The furnace comprises two principal chambers, a primary electrolytic chamber 4 and a secondary chamber 5, these chambers being separated by a septum or wall 6, the bottom flanges 7 50 of which serve to support the adjacent side lining 2. A set of anodes 8 extend into the primary chamber and are preferably made of some form of carbon. The primary chamber 4 is covered with a slab 9 of refractory material; and the gases liberated at the anodes are conducted away through flues 10. The secondary chamber 5 is fitted with a 55 spout 11 for conducting off the final product, such compartment having a cover 12 spaced from the container by an air tight

gasket to prevent the admission of air into the reaction chamber. An iron, nickel or carbon electrode 13 projects through the cover into the mass of electrolyte 14 disposed in the secondary chamber; the electrolyte in the primary chamber being designated 15. A body of heavy metal or alloy 16 is disposed in the bottom of the respective compartments or chambers, and a plurality of conduits, filled by said alloy, afford means for effectively circulating the heavy metal or alloy through and sealing the respective chambers. The circulation of the alloy may be effected either intermittently or continuously by mechanical means 70 or otherwise; a centrifugal pump 17 being shown in the drawings; and suitable means, such as a hopper 18, may be provided for permitting the continuous or intermittent introduction of the salt required in the electrolytic chamber. The secondary cathode 13 is adjustable in the air tight cover 12 and has a hole extending through its shank, the upper part of which is fitted with a valved pipe 19 for introducing nitrogen or ammonia 75 into the molten mass in the reaction chamber; and is also fitted with an oil feed device 20, through which fuel oil or other hydrocarbon may be introduced in carefully regulated quantities into the reactive chamber. An auxiliary supply pipe 21 extends through the side of the reaction chamber; its lower end being below the surface of the alloy, and such pipe may be used to introduce nitrogen or hydrocarbon, or both, directly 80 into the mass of molten metal, when desired, thus affording a means of preheating the nitrogen when desired. The cover 12 is also fitted with a specially constructed hopper 22, which has an air tight cover 85 and is so arranged that it may be filled with charcoal and then subjected to the action of a vacuum pump for the purpose of exhausting the air from the hopper and the charcoal contained therein, before it is charged into 90 the reaction chamber.

The molten cyanid is produced in the secondary chamber and normally rises to the level of the outlet before it is permitted to run off through spout 11; this spout may be 95 temporarily closed, however, to permit the cyanid to accumulate in the chamber to a much greater depth, before being tapped off.

The primary electrolyte may consist largely, at the beginning of the operation, of 100 molten barium chlorid—with a small proportion of sodium chlorid.

The electrolyte in the secondary chamber consists preferably of pure molten sodium cyanid, (although it may contain any proportion of pure barium carbid, cyanid, or other barium salt from which barium may be set free by sodium at the temperature of the operation). Both electrolytes rest on the surface of the molten lead in their re- 105

spective compartments. The anodes 8 and the cathode 13 are then raised slightly above the surface of the lead and the current is turned on.

5 The current density in both primary and secondary is determined by the electrode surface and the current, and the voltage is determined by the length of the column of electrolyte through which the current must 10 pass in each cell; the current density and voltage in each cell being regulated at will to maintain the electrolytes in molten condition, and to decompose them. The current liberates barium and sodium at the surface 15 of the lead in the primary cell, thereby producing an alloy of barium-lead-sodium, which is then conducted into or circulated through the secondary chamber by means of the centrifugal pump,—and soon becomes 20 practically homogeneous and of uniform temperature throughout the entire mass. The current then passes from the surface of the alloy in the secondary chamber (constituting the secondary anode) through the 25 molten cyanid to the solid cathode; the liberated anions (CN) combining with barium at the surface of the alloy to form barium cyanid, which accumulates in the electrolyte. The liberated anions (CN) may also 30 combine with sodium at the surface of the alloy, but this is of no consequence since the electrolyte consists of molten sodium cyanid.

The liberated anions cannot combine with 35 the heavy metal of the alloy, *e. g.*, to form a cyanid which would contaminate the secondary electrolyte or the product, and which would then yield, by electrolysis, lead at the solid cathode,—for reasons set forth in 40 application 575,819;—none of the heavy metals combining with carbon and nitrogen or cyanogen to form cyanids or cyanamids which are stable at the temperature of the 45 operation. This feature is of great importance in this process.

Metallic sodium is liberated at the cathode but as soon as an appreciable proportion of barium cyanid is present, which may be purposely introduced at the very start, the metallic 50 sodium displaces the barium which latter then immediately combines with carbon, free or combined, to form amorphous barium carbid; and this substance remains suspended in the cyanid. Nitrogen may 55 then be introduced through pipe 21 and will pass down through the hollow shank of the cathode 13 to the lower surface thereof, and there spread out in the form of a thin layer between the face of the cathode, or “plunger”, since it may be so termed, and the molten alloy, and thus come into effective 60 reactive contact with the suspended barium carbid with which it combines to produce barium cyanid. The barium in the barium 65 cyanid is then displaced by the metallic

sodium at the cathode, with the consequent production of sodium cyanid and metallic barium which latter again becomes available for the production of more carbid. If there is no free carbon present the barium 70 will seize upon one element of combined carbon in the sodium cyanid to form sodium cyanamid which is perfectly stable; but this latter substance is promptly reconverted into sodium cyanid as soon as 75 free carbon is added.

Carbon in the form of charcoal, from which the air and moisture have been removed by heat and vacuum may be introduced through the hopper into the reactive 80 chamber. Fuel oil may be introduced through the oil feed device under pressure, and will then come into contact with the red hot cyanid, which may also contain some cyanamid, below the surface of the plunger, 85 at which temperature the oil will be broken up into finely divided carbon, to wit, lamp black, and hydrogen; the latter substance escaping through the overflow spout.

As soon as a sufficient proportion of 90 barium has been incorporated into the alloy, and thence by electrolysis into the secondary electrolyte, it becomes unnecessary to supply more,—for the reason that the “reactive metal” is used over and over again, 95 and therefore no more barium chlorid need be added to the primary electrolyte, which may thereafter consist substantially of sodium chlorid. If there is any loss, however, of available barium in the alloy, or 100 of barium carbid or cyanid in the melt, through any unavoidable or inadvertent circumstance or by being withdrawn in the finished product, or for any other reason, the deficiency may be supplied from time 105 to time by adding barium chlorid to the electrolyte in the primary cell, or by supplying it in any other manner.

The temperature of the lower end of the secondary cathode or plunger if submerged 110 in the red hot alloy would be, of course, substantially equal to that of the molten metal itself; but when the face of the plunger is raised slightly above this efficient metallic heat conductor, I find that sufficient heat 115 may be conducted away through the shank of the plunger to the heavy copper conductors on the outside of the furnace to substantially reduce the temperature of the face and entire lower end of the plunger and of the molten cyanid in immediate contact therewith, and this is a fact of considerable importance when employing ammonia as the nitrogenous reagent.

The combination of the nitrogen of the 120 ammonia with the amorphous carbid suspended in the molten cyanid takes place with great rapidity and efficiency owing to the fact that such nitrogen is liberated in the atomic or nascent form in contact with 130

the carbid, whereas if the ammonia is first introduced into the red hot alloy it is there partly decomposed into its elements, nitrogen (in the atomic state) and hydrogen, but this atomic nitrogen, unless instantly absorbed, passes into the molecular state, (N_2). When molecular nitrogen rises into the molten cyanid it does not combine with the suspended carbid with such avidity, as does the atomic nitrogen. The absorption of molecular nitrogen, in other words, is effected somewhat more slowly than the absorption of atomic nitrogen. While it is disadvantageous for this reason to first introduce ammonia into the red hot alloy and then permit the nitrogen to rise into the cyanid, this objection does not hold with nitrogen obtained from the air,—*i. e.*, molecular nitrogen, which may advantageously be first introduced into the molten metal for the purpose of preheating it before it comes into contact with the carbid. The auxiliary nitrogen pipe 21 may be used for this purpose.

25 When the reaction vessel is sufficiently full of cyanid it becomes necessary to finish or clarify the charge. The flow of gas should be stopped, and the sodium liberated a short time longer in order to insure the decomposition of all of the barium cyanid by sodium—which should be in excess in the alloy—after which the suspended materials in the mass should be allowed to settle.

30 Barium carbid has a specific gravity somewhat greater than that of molten cyanid, and it, together with the excess carbon, will settle in the course of time through the tranquil, undisturbed melt to the surface of the alloy after which the clear molten cyanid, 40 or any part of it, may be tapped off at one of the spouts above the surface of the alloy.

Another method of finishing a charge of cyanid consists in limiting or withdrawing the supply of sodium in the bath and in the 45 alloy so that all of the residual suspended carbon and carbid may be permanently converted into barium cyanid, and the melt will consist of a clear molten mixture of substantially pure sodium cyanid and barium cyanid which may be drawn off and utilized as such.

50 The respective proportions of the two cyanids may be controlled at will; but in general the sodium cyanid should be greatly in excess.

55 It will be apparent from a consideration of the above reactions that a free “reactive metal” must be employed at some point in the cycle, or in lieu thereof a compound 60 which will yield a free “reactive metal” at some point in the cycle, and that the use of any salt or compound which when introduced into the molten mass or employed under any of the conditions of the process 65 will yield such “reactive metal”, is within

the scope of my invention. It will be apparent, also, that a carbid, nitrid, cyanamid, or cyanid of the “reactive metal”, if of sufficient purity and in suitable physical condition may be employed at the outset instead of the “reactive metal” itself, and that this is possible by reason of the fact that the initial carbid or nitrid, under the conditions of the process, will be converted into either cyanamid or cyanid of the “reactive metal”, and that the alkali metal,—sodium or potassium will thereupon liberate and set free the “reactive metal”—in metallic form. Other “reactive metal” salts may be similarly introduced and decomposed with consequent liberation of a free “reactive metal” but the method is slightly objectionable for the reason that it introduces an impurity or diluent, *e. g.*, sodium chlorid into the final cyanid. Thus barium chlorid, lithium chlorid, etc., if introduced into the molten cyanid will melt and dissolve therein and come into contact with the liberated sodium or potassium or that contained in the alloy, which will then decompose such chlorids with the formation of sodium or potassium chlorids, and metallic barium, or metallic lithium will be liberated, according to the following equation:

Other “reactive metals” may be employed instead of barium,—notably, lithium, strontium, and calcium, in which event the reactions will be quite similar to those indicated for barium.

The “reactive metals” manganese, cerium, chromium, titanium, vanadium, etc., will also bring about the synthesis of sodium cyanid under this process, although the mechanism of the intermediate reactions is not the same in all cases, and the process is somewhat slower.

What I claim, is:

1. In a process of producing alkali-metal-cyanogen compounds and the like, the steps which comprise separating alkali-metal from a molten metallic bath and reacting on the separated metal with a nitrogen-carbon compound.

2. In a process of producing alkali-metal-cyanogen compounds and the like, the steps which consist in electrolytically separating alkali-metal from a molten metallic bath and reacting on the separated metal with a nitrogen-carbon compound.

3. In a process of producing alkali-metal-cyanogen compounds and the like the steps which consist in electrolytically depositing alkali-metal of the compound to be produced and reacting on an impalpable amorphous carbid with a nitrogenous reagent in the presence of said electrolytically deposited metal.

4. In a process of producing alkali-metal

- cyanogen compounds and the like, the steps which consist in electrolytically depositing alkali metal of the compound to be produced, and similarly depositing a "reactive metal," 5 reacting on the "reactive metal" with carbonaceous and nitrogenous reagents to form a nitrogen-carbon compound of such metal and substituting the alkali-metal aforesaid for the "reactive metal" in said compound.
- 10 5. In a process of producing cyanogen compounds and the like, the steps which consist in effecting a reaction between electrolytically liberated "reactive metal" and a carbonaceous reagent within a bath of fused 70
- 15 mixed salts and reacting on the compound so formed with a nitrogenous reagent.
6. In a process of producing cyanogen compounds and the like the step which comprises effecting a chemical reaction between 20 a carbonaceous reagent and an electrolytically liberated metal within a bath of fused salt to form an amorphous carbon compound of said metal.
- 25 7. In a process of producing cyanogen compounds and the like, the steps which comprise effecting a chemical reaction between a carbonaceous reagent and an electrolytically liberated metal within a bath of fused salt to form an amorphous carbon 80
- 30 compound of said metal, and reacting on said carbon compound with a nitrogenous reagent.
- 35 8. In a process of producing cyanogen compounds and the like, the steps which comprise effecting a chemical reaction between a carbonaceous reagent and an electrolytically liberated metal to form an amorphous carbon compound of said metal, and reacting on said carbon compound with a nitrogenous 85
- 40 reagent to form a carbon-nitrogen compound of said metal, the reactions taking place within a bath of fused salt.
- 45 9. In a process of producing cyanogen compounds and the like the steps which comprise electrolytically depositing a metal from a bath of fused salt and reacting on such metal with a carbonaceous reagent to 90
- 50 form a carbon compound, said compound being held in suspension in the salt, and reacting on the suspended carbon compound with a nitrogenous reagent.
- 55 10. In a process of producing cyanogen compounds and the like the steps which comprise electrolytically depositing a metal from a bath of mixed fused cyanogen compounds, the radical forming constituents of one at least of which are the same as those of the compound to be produced, one of said fused compounds including an alkaline 100
- 60 metal and another a metal belonging to a different group of metals, and reacting on such metal with carbonaceous reagent.
- 65 11. In a process of producing cyanogen compounds and the like the steps which comprise electrolytically depositing a metal 105
- from a bath of mixed fused alkali and alkaline earth cyanogen compounds, and reacting thereon in such bath with carbonaceous and nitrogenous reagents to form a nitrogen-carbon compound of the metal.
12. In a process of producing a compound consisting of a metal and a combination of elements capable of forming a radical the steps which consist in electrolytically depositing a metal from a bath which comprises the said combination of elements and reacting on said metal with a reagent to 110
13. The process of producing alkali-metal cyanogen compounds and the like, which includes liberating alkali-metal by passing a current of electricity through a fused bath from a substance which contains such alkali-metal as one of the constituents thereof, forming a carbon-nitrogen compound in said bath and reacting on the liberated alkali-metal with said compound.
14. The process of producing alkali-metal cyanogen compounds and the like, which includes liberating an alkali-metal and a "reactive metal" by passing a current of electricity through a fused bath from a body of alloy which contains said metals, forming a carbon-nitrogen compound of the "reactive metal" in said bath and reacting on the liberated alkali-metal with said compound.
15. In a process of producing cyanogen compounds and the like, the steps which consist in electrolytically liberating a "reactive metal", reacting thereon with a molten carbonaceous reagent to form a carbid, at a temperature below that at which such carbid will fuse, and effecting a reaction between said carbid and a nitrogenous reagent.
16. The process of forming a carbon-nitrogen compound which comprises electrolytically depositing a plurality of metals in the presence of nitrogenous and carbonaceous reagents, one of said metals forming a nitrogen-carbon compound with constituents of said reagents and another of said metals being thereafter substituted in said compound for the first.
17. The process of producing alkali-metal cyanogen compounds and the like, which involves reacting with a carbonaceous reagent on free "reactive-metal" to form a carbon compound thereof, reacting on said compound with a nitrogenous reagent to 120
18. The process of producing a carbon-nitrogen compound which includes forming a carbon compound within a mass of electrolyte through which an electric current is flowing, said electrolyte being in contact 125
- 130

with a fluid body of relatively high density which supplies at least one of the ingredients of the compound aforesaid, and reacting on said compound with a nitrogenous reagent.

- 5 19. The process of producing a carbon-nitrogen compound which includes forming a carbon compound within a mass of electrolyte through which an electric current is flowing said electrolyte being in contact with
10 a fluid body of relatively high density which

supplies at least one of the ingredients of the compound aforesaid, and reacting on said compound while in said electrolyte, with a nitrogenous reagent.

In witness whereof, I subscribe my signature, in the presence of two witnesses.

CHARLES E. ACKER.

Witnesses:

WALDO M. CHAPIN,
WILLIAM C. LANG.
